UNITED STATES PATENT OFFICE.

AMY FLORENCE BROWNING, OF DEVON, PENNSYLVANIA.

UNDERGARMENT.

1,034,071.

Specification of Letters Patent. Patented July 30, 1912.

Application filed January 20, 1910. Serial No. 539,029.

To all whom it may concern:

Be it known that I, AMY FLORENCE BROWNING, a citizen of the United States, residing at Devon, in the county of Chester 5 and State of Pennsylvania, have invented a new and useful Undergarment, of which the following is a specification.

My invention relates to improvements in combined or integral corset covers and leg 10 coverings of the style known as "princess." These garments, as is well known, are made from a non-stretchable or non-elastic material such as muslin. They are required to fit closely to the figure at the waist and over 15 the hips so as not to interfere with the fit of a close fitting "princess" dress, and are adapted to open from the neck opening to a point at or near the crotch to permit the garment to be drawn on and off. This 20 opening has been a serious objection to the use of undergarments of this character as heretofore made. If formed in the front of the garment, the yoke has been split or divided, which is particularly objectionable 25 when a close fit across the upper portion of the bust is desired as, for example, when the yoke is visible through the dress. Such an opening also necessarily necessitates the 30 splitting or dividing of the yoke, which is objectionable when the same is of a form or quality to be permanently injured thereby, as when a separate ornamental yoke is secured to the garment. On the other hand, 35 if the opening is formed in the back of the garment, the fastening and unfastening of the garment by the wearer is rendered difficult.

The objects of my invention are to improve the general fit of an undergarment of 40 the character described, and to so form the same that although made of a non-stretchable or non-elastic material it may be fastened up the front and at the same time provided, in the front, with a closed or integral 45 yoke.

Referring to the drawings which are 50 illustrative of specific embodiments of my invention as applied to combined corset covers and drawers: Figure 1 is a front view of a figure dressed in my improved garment. Fig. 2 is a rear view of a figure dressed in the garment. Fig. 3 is a front elevation of a garment of a slightly different form. Fig. 4 is a rear elevation of 55 same. Fig. 5 is a detail of the buttons and

button-holes for fastening the garment up the front.

Similar numerals refer to similar parts throughout the several views.

My improved garment comprises a single 60 unitary structure in which the body portion 7 is cut to fit closely to the figure at the waist and over the hips, the waist portion of the garment being smaller or of less circumference than the wearer's hips. The 65 yoke 8 may either be formed from the piece or pieces of cloth forming the front of the garment, as shown in Fig. 3, in which figure tucks 28 are shown for purposes of ornamentation and to conceal seam 14; or the 70 yoke may comprise a separate piece of embroidered fabric, lace, etc., sewed to the front of the garment as shown in Fig. 1. In either case it is not divided as heretofore and is of closed or integral form and has a continuous or permanently unbroken upper margin. Below the yoke and extending downwardly 75 through the narrowed waist portion of the garment is the vertically disposed slit or opening 12. This slit preferably extends to 80 a point a short distance below the hips, but, if preferred, it may obviously be continued to or past the crotch.

The extent of the opening at the top of 85 the garment is sufficient to permit the top portion thereof to pass readily over the hips, while the location and extent of slit 12 relatively to the opening at the top of the garment and the narrowed waist portion, is 90 such that when the slit is free to open, or unfastened, the narrowed waist portion may be slipped over the hips of the wearer to permit the garment to be drawn on or off, and when the slit is closed by securing the sides 95 of the same together, the garment will fit closely to the contour of the figure at the waist and hips. It will be understood that as the opening at the top of the garment is adapted to pass over the hips it will ordinarily be of relatively large extent and that 100 by extending slit or opening 12 to a point considerably above the waist line it will be possible to utilize said opening 12 and said top opening to permit the passing of the arms through arm holes 6. That is, as the slit opens or spreads, a substantial movement 105 of the side of body portion 7 between the slit and the arm to be passed through the arm hole is permitted.

It will thus be seen that by my invention 110

there is provided an extremely compact and well fitting undergarment, which, although made from a non-stretchable or non-elastic material and provided in the front with the 5 closed or integral yoke heretofore only attained in garments of this class fastening up the back, may be fastened and unfastened in the front and readily slipped on or off.

It will be understood that the extent and 10 form of the opening at the top and the arm holes, and the length or location of slit 12, are capable of sufficient relative variation to permit either changes in the specific form of the garment or its use by persons of 15 widely varying proportions. Drawing strings 9 and 13 may be provided if preferred either at the top opening or about the waist, and supporting members or shoulder straps 11 may be either integral with body 20 portion 7 or secured at points 10 on the margin of the top opening.

In my preferred construction, in which I 25 secure an exceptionally well fitting and satisfactory garment, seam 14 extends down the middle and front of the garment from the top opening to point 18, shaping in at the waist and then out and curving slightly at the lower end to form the crotch. It is left open from a point between the top opening and the waist line a substantial distance above the latter, to a substantial distance below the same to form slit 12. Attached to edge 19 of the opened part and to a similar 30 edge, not shown, on the other side of the slit, are flaps 17, made from a strip of material folded once longitudinally and once laterally. The raw edges of this strip are turned in and the strip sewed to raw edge 19 and to a similar edge, not shown, of the 35 part of the garment forming slit 12, said edges being caught between the edges of the strip, the ends of which are sewed together. Button-holes 20 are worked in the flap on one side of the slit and buttons 16 are sewed

45 to the inside of the flap on the other side. This permits the inward buttoning of the flaps to conceal and cover the buttons. Gores 21 extend from the bust to the bottom of the garment, shaping in at the waist and out at the hips. Darts 22 and 23, there being two 50 of each, start near arm holes 6 and extend to the largest part of the hips. Seams 24, in the back, at each side of the middle, extend from the top of the garment to the bottom, shaping in at the waist and out over the 55 hips flaring somewhat as a gore. Seam 25 extends between seams 24 at a point a little above the waist line. Seam 26 in the middle of the back, extends downwardly from seam 25 curving inwardly at a point near the bottom 60 to point 18 in the crotch. From point 18, at which point also ends seam 14, the two seams 27 extend to the bottom of the drawers leg 15, forming the inside seam of the same.

65 What I claim is:

As a new article of manufacture, a princess undergarment made from a non-elastic or unstretchable material and comprising a combined corset cover and leg covering 70 adapted to fit the contour of the waist and provided in the narrowed waist portion thereof with a downwardly extending slit, said garment having an opening at the top adapted to pass over the hips, a closed or 75 integral yoke, having a continuous or permanently unbroken upper margin, above the upper end of the downwardly extending slit and separating said slit from the top opening, and means for closing said slit, the garment adapted to be drawn on or off when the slit is free to open and to fit the contour of the waist when the slit is closed.

80 AMY FLORENCE BROWNING.
